UNITED STATES PATENT OFFICE.

MELVIN A. YEAKLEY, OF CANTON, OHIO, ASSIGNOR TO JOHN E. McLAIN, OF CANTON, OHIO.

TROLLEY-CATCHER.

1,146,833.

Specification of Letters Patent. Patented July 20, 1915.

Application filed June 1, 1908. Serial No. 436,147.

To all whom it may concern:

Be it known that I, MELVIN A. YEAKLEY, a citizen of the United States, residing at Canton, in the county of Stark and State of Ohio, have invented certain new and useful Improvements in Trolley-Catchers, of which the following is a specification, reference being had therein to the accompanying drawings.

10 This invention relates to means for maintaining a trolley rope taut as the trolley end of the trolley pole moves up and down to adapt itself to different heights of the wire, and to catch and hold the paying out device 15 for the trolley rope when such paying out becomes unduly rapid as when the trolley jumps the wire. Such means are commonly known as trolley catchers.

To prevent the unduly rapid paying out 20 of the trolley rope, it has heretofore been largely the practice to provide dogs which, upon the too rapid movement of the rope drum, would rigidly lock the drum to a stationary portion or stop.

25 More specifically, the structure has comprised a drum for the trolley rope upon which are mounted centrifugal dogs which, upon undue speed of the drum, fly outwardly and engage projections or teeth 30 upon the inside of the casing. The means described results in an abrupt stop thereby severely shocking and straining the parts with the likelihood of causing breakage. Particularly is there a liability of breaking 35 the teeth upon the casing, and where these teeth are integral with the casing, as is almost universally the practice, their breakage necessitates the provision of a new casing.

40 It is an object of my invention to obviate the disadvantages noted in devices of this character and to this end a yielding device at all times active is included in the means for stopping the winding drum, whereby 45 the impact of the parts is cushioned. This yielding device may be located at any suitable point of the stopping means and may consist of a spring, a friction device or other suitable means which will permit a "give" 50

55 of the parts upon the stoppage of the drum and at the instant of engagement of the elements for stopping the drum's rotation.

In the embodiment of the invention which has been chosen to illustrate it, and which is shown in the accompanying drawings, the

yielding device is shown as a normally active coiled spring. In this embodiment, also, instead of being mounted upon a drum the dogs are mounted upon a separate member which is driven by the drum through 60 the spring referred to. It will be seen that upon engagement of the dogs and a stoppage of the member upon which they are mounted the spring will prevent the abrupt stoppage of the drum.

65 Another object of my invention is to provide means which tend to retain the centrifugal stop dog in contact with a positive stop in the mechanism when said dog has been thrown out by centrifugal force into 70 engagement with said stop to check the upward travel of the trolley pole, so that thereafter, in the event the trolley pole rebounds or is moved downwardly for any reason, the attendant rewinding of the 75 trolley rope on the rope drum, under the action of the slack-absorbing spring, will be accompanied by an effort on the part of said means to retain the stop dog in the path of said positive stop. This being the 80 case, when the rebound of the trolley pole, or its said downward travel is completed and the pole again starts to move upwardly, the centrifugal stop dog will instantly engage the positive stop and prevent the further upward travel of the trolley pole. If 85 a spring tending to turn the drum to wind up a trolley rope is wound too tight, the free movement of the trolley in going from a low to a higher portion of the trolley wire will be retarded and the trolley is liable to 90 leave the wire. It is therefore necessary in order that the trolley may adapt itself readily to different heights of the trolley wire, that the spring referred to shall not 95 be wound too tight.

96 It is a further object of the invention, therefore, to provide means for automatically preventing the too tight winding of the spring, both for the purpose just stated 100 and in order to prevent breakage of the spring.

Other objects of the invention will appear hereinafter.

105 Figure 1 is a vertical section on the line $a-b$ of Fig. 2 looking from the right. Fig. 2 is a section through the casing on the line $c-d$ of Fig. 1 looking in the direction of the arrow. Fig. 3 is a section on the line $e-f$ of Fig. 1 looking from the left, the left 110

hand half of the casing being removed. Fig. 4 is a section on the line *g*—*h* of Fig. 1 looking in the direction of the arrow. Fig. 5 is a section through the casing on the line *i*—*k* of Fig. 1, showing the interior mechanism when looking in the direction of the arrow. Fig. 6 is a side elevation of a portion of the casing and the bracket by which it is secured to the car. Fig. 7 is a section on the line *l*—*m*, Fig. 6. Fig. 8 is a view similar to Fig. 3 of a slightly modified form of construction. Fig. 9 is a view similar to Fig. 2 of the said slightly modified construction, the centrifugal dog and its counter-balancing weight being removed. Fig. 10 is a section on the line 10—10—, Fig. 11, and is of another modified construction. Fig. 11 is a section on the line 11—11, Fig. 10. Fig. 12 is a fragmentary view of the drum and associated parts showing the connection of the trolley rope with the drum.

Referring to the drawings—The casing is divided vertically and the two halves 1 and 2 are held together by a bolt 3 which also serves as an axle for the interior mechanism. When assembled the casing has an opening 4 through which the trolley rope 5 passes and there is an opening 6 beneath the winding drum 7. The winding drum 7 is journaled on the bolt 3. Also journaled on the bolt 3 is the dog-carrying member 8 which is separate from the drum and between which driving connection is established by means of a spring 9.

Upon the member 8 are pins 10 and 11 located on opposite sides of its center. Upon these pins are respectively pivoted the centrifugal dog 12 and its counter weight 13. The dog and counter weight are connected by a spring link 14 and a spring 15, coiled about the pin 10 and engaging at one end with the dog 12 and at the other end with the member 8, tends to hold the dog out of engagement with the teeth 16 of the ratchet 17 upon the inside of the casing. Upon undue speed the force of the spring will be overcome and the dog will engage with the ratchet teeth. The utility of the counter-weight will be apparent when it is considered that the bolt 3 is horizontal and that therefore in the position shown (see Fig. 2) the weight of the dog opposes the centrifugal force. When the dog-carrying member has turned through 180 degrees and the dog occupies the position shown in the drawing as occupied by the counterweight, the weight of the dog will be added to the centrifugal force in producing a tendency for it to move outward. With the counterweight 13 and the dog linked together, as shown, their weights are balanced at all times so that gravity has no influence upon the dog, which responds solely to the centrifugal force. The counterweight might also be adapted to act as a dog but ordinarily one

dog will prove sufficient. The link 14, being of spring material, the parts are not hampered in their movements as would be the case if this link were rigid.

The spring 9 (see Fig. 3) which constitutes a flexible driving connection between the drum 7 and the dog-carrying member 8, is looped about a pin 17 upon the drum spider. The outer leaf 9^a of this spring is coiled about the hub of the member 8 and its end is secured thereto by being bent into a recess in the hub, as shown at 9^a. The inner leaf 9^b is unsecured, other than at the looped end, except as it is confined and bound by the outer leaf.

It will be apparent that as the pin 17 moves in a clockwise direction about the hub (viewing the parts as in Fig. 3), which takes place when the dog-carrying member is arrested by the engagement of its dog with the ratchet upon the casing, the end of the inner leaf will be bound between the outer leaf and the hub of the dog-carrying member so that the spring as a whole will be stiffened and a considerable resistance opposed to the turning of the drum with relation to the dog-carrying member. Upon movement of the pin in the other direction, however, the binding of the inner leaf by the outer one will be relieved so that the former can more easily slide upon the latter whereby the tension of the spring as a whole is decreased. With the arrangement as shown, therefore, and with particular reference to Fig. 3, when the trolley jumps the wire and the dogs act to lock their carrying member against rotation, the rotation of the winding drum in a clockwise direction is retarded by a large spring tension. When, however, the trolley has reached the upward limit of its movement, if it starts to rebound downwardly, the drum starts to move in a counter-clockwise direction whereupon the binding of the inner leaf of the spring by the outer is relieved and the tension of the spring as a whole, which would tend to produce a rebound, of the dog-carrying member, is greatly reduced.

Encircling the bolt 3 is a plate 18 having a ratchet 19 upon its hub. The hub of the plate 18 is preferably loosely sleeved over a reduced portion of the hub for the drum 7. The plate 18 and its ratchet are held against rotation by means of a projection 20 which projects into a recess 21 in the casing. Pivoted at 22 upon the winding drum is a pawl 23 having its nose normally held in engagement with the ratchet 19 by means of a spring 24 which is coiled about the pivot 22 and has one end in engagement with the drum while the other end is in engagement with the tail of the pawl, as shown. The tail of the pawl extends over a hole 25 in the drum. This hole is key-hole shaped, that is, is wider at one end than at the other

80

130

(the wide end being at the right hand in Fig. 4). The knotted end of the trolley rope may be passed through the wide portion of the hole 25 and the rope being then drawn into the narrow portion after the knot has been passed within the drum, the end of the rope is securely fastened to the drum by reason of the fact that the knot cannot pass through the narrow portion of the hole. Furthermore, the knot operates to elevate the tail end of the pawl thereby throwing the nose out of engagement with the ratchet 19.

The spring 26 is for turning the drum to maintain the trolley rope taut as the trolley adapts itself to varying heights of the trolley wire. This spring engages at one end with the hub of the winding drum and at the other end is secured to a segmental spring 27 which rests upon the interior of the casing. The engagement of one end of the spring 26 with the hub of the winding drum is preferably accomplished by bending the end of the spring into a recess as is clearly shown in Fig. 5. The side of this recess against which the bent end of the spring is drawn when the spring is wound is at a somewhat abrupt angle with the bottom of the recess so that movement of the end of the spring in this direction is arrested. The other side of the recess, however, is a gradual incline, as shown, so that if the parts are turned to unwind the spring, the end of the spring will slide out of the recess and about the hub thereby preventing breakage of the spring in case an attempt is made to wind it in the wrong direction. The manner of securing the other end of the spring, namely by means of the segmental spring 27 sliding upon the interior of the casing, prevents the too tight winding of the spring. If an attempt is made to wind the spring beyond a certain tension, the segment 27 will slide and prevent it. In some circumstances the friction between the segment 27 and a smooth casing interior might be sufficient, but it is preferred to provide teeth 28 as shown upon the casing, in the recesses between which the projection 29 upon the segment 27 extends. Upon a too tight winding of the spring, this projection will be withdrawn from the recess in which it may be located and the segment will slide about the interior of the casing and relieve the surplus tension.

For securing the apparatus to a car, the right hand end of the casing as viewed in Fig. 1, is provided with ribs 30 upon its exterior. From any suitable number of ribs extend projections 31. In securing the device to a car a bracket 32 is fastened to the car and this bracket has a central circular recess 33 with an encircling rim 34. In the face of this rim are cut notches, as 35, extending laterally from which are un-

dercut recesses as 36, these notches and recesses being adapted to receive the projections 31, the projections being entered through the notches and then entered within the undercut recesses by slightly turning 70 the apparatus about its axis. In this manner bayonet joints are formed which secure the bracket and trolley catcher together. To secure the catcher and bracket in locked relation an arm 37 extends from the casing 75 of the catcher and in this arm is mounted a slideable bolt 38 which, when the catcher is in locking position upon the bracket, will register with a socket 39 in the rim of the bracket, and the bolt being inserted in this 80 socket the catcher is locked in position on the bracket. The ribs 30 rest upon the interior of the rim 34 and any available number may be employed, some of them, as shown in Fig. 5, being without projections 85 31, if desired.

In the operation of the catcher, assuming that the slack-absorbing spring 26 is unwound, possibly the simplest manner of winding it up and placing the catcher in 90 condition for operation, is to loop a section of trolley rope around the drum, then holding the respective ends of the loop firmly in either hand, to seesaw the rope back and forth around the drum bearing against the 95 periphery of the drum when pulling in the direction to wind the said spring 26, and easing up when pulling in the reverse direction. This is continued until a clattering or chattering noise is heard which indicates 100 that the segment 27 is slipping about the interior of the casing. The loop of the trolley rope is then withdrawn from the catcher and the lower knotted end of it is introduced through the rope opening 25 and the 105 cord is drawn back into the narrow part of said opening so as to throw the said knotted end against the free end or tail of the pawl simultaneously swinging the nose of the pawl out of engagement with the ratchet 110 19 and releasing the drum and its slack absorbing spring; the latter then acts to rotate the drum and wind up the desired amount of trolley rope upon the drum.

When the catcher is not in use and the 115 trolley rope is removed, the spring 26 would quickly unwind, necessitating its rewinding before it could be placed in use, unless means were provided for preventing it. In the apparatus shown, when the knot of the trolley rope is removed from the hole 25 the nose of the pawl 23 is thrown into engagement with the stationary ratchet 19 so that the spring is prevented from unwinding. When, however, the catcher is placed in service, the 120 pawl 23 is removed from the ratchet 19 upon the insertion of the knot of the trolley rope beneath the tail of the pawl, then the drum is free to move under the action of the 125 spring and maintain the trolley rope taut 130

under the raising and lowering of the trolley in adapting itself to varying heights of the trolley wire. If, however, the trolley should leave the wire the drum would rotate 5 at such a rate that the dog 12 would fly outwardly into engagement with the stationary ratchet 16, whereupon the drum would be stopped, and the trolley caught, the stoppage being cushioned by the spring 9, which, 10 under these circumstances, exerts a considerable tension, the tension of this spring being comparatively small in retracting the trolley, as has been already noted.

Another effect of the spring 9 is to be 15 noted. When the trolley rebounds after being caught, the drum turns to take up the slack rope. If the dog is mounted on the drum, this would result in the backing off of the dog from the ratchet whereupon the dog would be retracted and the drum and trolley released. It will be understood that the spring 9 acts as well to tend to retain the centrifugal dog 12 in the path of and in contact with the tooth with which it has been 20 thrown into engagement, as to cushion the shock between the drum and the casing when the drum is suddenly and violently rotated. This being the case, the mechanism is adapted to instantly stop the upward travel of a 25 trolley pole when it has rebounded or been forced downwardly after being held from further upward travel by engagement of the centrifugal dog 12 with one of the ratchet teeth. In case of a rebound the spring 30 will take up the slack occasioned by the rebound but the member 8 will not rotate in the winding up direction during this rebound, nor is the dog 12 removed from the path of the ratchet tooth which is engaged 35 40 when it is thrown outwardly; on the contrary, the dog remains in said path due to the action of the inner end of the spring 9, which, when the spring 20 is relaxed during the rebound of the trolley pole, tends to unwind and exerts a pressure on the member 8 in clockwise direction (as viewed in Fig. 3). The rebound of the trolley pole occupies such a short interval of time that the dog 12 is not moved from the path of the ratchet 45 50 tooth and is therefore ready to engage the ratchet tooth before or the instant the pole starts upwardly after the rebound. Furthermore, when the trolley has left the overhead conductor and the trolley pole has been stopped by the action of the catcher from further upward travel of the trolley, should the said pole engage with a span wire, or any superstructure for the overhead conductor and have its trolley end forced downwardly, the winding drum 7 will instantly 55 60 and freely act to wind up the trolley rope slack and when the said trolley pole is again free to swing upwardly at its trolley end, such movement will be immediately stopped 65 by the engagement of the dog 12 with the

ratchet 16, which has been retained in readiness for instant stoppage action.

While in the above described trolley catcher embodying my invention a normally acting yielding driving connection is shown 70 between the drum 7 and the dog-carrying member 8, the driving connection between these elements may be positive and supplemental means may be employed for tending to retain the centrifugal dog in ratchet-engaging position during the winding of the drum when a rebound of the trolley pole occurs. Such a construction I have illustrated in Figs. 8 and 9. In this construction the spring 9 is made very light and thin, it being intended simply for the purpose of tending to retain the centrifugal dog 12 in the path of the ratchet 16 during the winding up action of the drum 7 when a rebound of the trolley pole occurs. 75

40 are driving lugs on the outer face of the drum 7.

41 are driving lugs on the periphery of the dog-carrying member 8, and with which the said driving lugs 40 are adapted to engage in order to cause the rotation of the dog-carrying member in anti-clockwise direction with the drum 7, or during the rope winding up action of the drum. 80

42 are driving lugs on the periphery of the dog carrying member 8 with which the driving lugs 40 on the drum are adapted to engage to cause the rotation of the said member with the drum in clockwise direction. 90

In the construction last described, it will be understood that the spring 9 merely serves the purpose of adapting the operation of the centrifugal dog to act substantially instantly after the rebound of the 105 trolley pole, following the action of the device in stopping the upward travel of the said pole.

In Figs. 10 and 11 I have illustrated another modification of my invention. The 110 elements shown in these figures, in so far as possible, are designated by the same reference numerals hereinbefore employed to designate like parts and elements. In this embodiment, however, the centrifugal dog 115 12 is pivoted directly to the drum 7, as is also the counterbalancing weight 13.

44 is an intermediate member or ring loosely mounted on the shaft 3 and having an internal ratchet 45, with the teeth of which the centrifugal dog 12 is adapted to engage. On its periphery, this intermediate member 44 carries, preferably at diametrically opposite points, outwardly extending projections 46, 47. 120

48, 49 are inwardly projecting lugs or stops carried by the part 1 of the casing, and arranged in the plane of the projections 46, 47 on the intermediate member 44. Between these stops or projections 48, 49 the 125 130

casing may be grooved or recessed at 50 to receive and retain the cushion spring 51 which may be of less length than the groove 50 arranged at one side of the stop 48 and 5 between it and the projection 46 on the intermediate member, and at 52 to receive and retain the spring 53 between the stop 49 on the casing and the projection 47 on the intermediate member.

10 The cushion spring 51 is adapted to buff or cushion the blow between the intermediate member 44 and the casing 1 when the dog 12 under the unduly rapid rotation of the drum 7 engages a tooth on the ratchet 45 and rotates the intermediate member 44. The stoppage of the upward travel of the trolley pole under such conditions is effected with the cushioning action of the spring 51 between the casing 1 and the projection 46 on the intermediate member 44.

15 The spring 53 is a light, relatively weak coiled spring, the function of which is to retain the intermediate member 44 and the centrifugal stop dog 12 in engagement during the rope winding up action of the drum 7 incident to the rebound or downward movement of the trolley pole after its upward travel has once been stopped by the action of the catcher. I have found it advantageous to so make and hold the spring 20 53 in the casing 1, that its compression will require several times the power that the spring will deliver when expanding,—that is, the spring 53 is intended to be strong 25 enough or to have expansive force sufficient only to maintain the dog 12 in engagement with a ratchet tooth, but to be so arranged and constructed as to assist the spring 51 in yieldingly arresting the unwinding of the 30 trolley cord. In the device illustrated, I have shown the groove 52 in the casing 1 in which the said spring is arranged, to taper in diameter from the stop 48 to the stop 49, so that the compression of the 35 spring 53 must be effected against the frictional resistance of the walls of said groove 52 to the compression of the said spring therealong, while the spring is free to expand from the stop 49 toward the stop 48.

40 50 Many alterations in the construction, and many widely differing embodiments and applications of my invention will suggest themselves to those skilled in the art of making trolley catchers, without departing from the scope and spirit of the appended claims.

55 My disclosures and description herein are purely illustrative and are not intended to be in any sense limiting.

60 What I claim is—

1. In a trolley catcher, the combination with a drum, means for turning said drum to wind up the trolley rope thereon, and a casing, of means interposed between said 65 drum and casing for stopping the rotation

of the drum, the said means including a centrifugal dog and normally active means for cushioning the impact incident to the action of the dog to stop the rotation of the drum.

2. In a trolley catcher, the combination 70 with a drum, a single spring for turning said drum to wind up the trolley rope thereon, and a casing having stops, of means including a normally active spring and a dog arranged to engage one of said stops for stopping said drum and for cushioning the impact incident to the action of said dog to stop the rotation of said drum.

25 3. In a trolley catcher, the combination with a drum, a spring for turning said drum 80 to wind up the trolley rope thereon, and a casing, of means including a ratchet, a centrifugal dog actuated by said drum and adapted to engage the ratchet to stop the rotation of said drum, and a spring normally 85 free to be operated located between said drum and casing for cushioning the impact incident to the action of said dog to stop the rotation of said drum.

4. In a trolley catcher, the combination 90 with a winding drum, of a dog-carrying member separate from said drum, a centrifugal dog mounted upon said member, a yielding driving connection at all times active between said member and drum, and 95 a ratchet stationary with relation to said member and drum and adapted to be engaged by said dog to stop said drum.

5. In a trolley catcher, the combination 100 with a winding drum, of means for stopping said drum, comprising a centrifugal dog, a ratchet, and a driving connection between said drum and dog including a yielding element at all times active for cushioning the impact when said dog engages said ratchet. 105

6. In a trolley catcher, the combination 110 with a winding drum, of a centrifugal dog, a normally yielding driving connection between said dog and said drum at all times during the unwinding movements of said drum tending to effect the simultaneous rotation of said drum and dog, and a ratchet stationary with relation to said drum and adapted to be engaged by said dog to arrest said drum.

7. In a trolley catcher, the combination 115 with a winding drum, of a centrifugal dog, means connecting said dog and said drum including a spring at all times active as a driving connection between the drum and 120 dog and rotatable with said drum, and a ratchet stationary with relation to said drum and adapted to be engaged by said dog to arrest said drum.

8. In a trolley catcher, the combination 125 with a winding drum, of a spring for turning said drum to maintain the trolley rope taut, a dog-carrying member separate from said drum, a centrifugal dog upon said member, a yielding driving connection between 130

said member and drum at all times active during the unwinding movements of said drum to cause said drum and member to rotate together, and a ratchet stationary with relation to said member and drum and adapted to be engaged by said dog to stop said drum.

9. In a trolley catcher, the combination with a winding drum, of a spring for turning said drum to maintain the trolley rope taut, and means for arresting said drum comprising a centrifugal dog, a ratchet and means at all times active between said dog and drum for cushioning the impact when said dog engages said ratchet.

10. In a trolley catcher, the combination with a winding drum, of a spring for turning said drum to maintain the trolley rope taut, a ratchet, a centrifugal dog adapted to engage said ratchet, and a yielding driving connection between said dog and drum normally active to transmit motion from the drum to the dog.

11. In a trolley catcher, the combination with a winding drum, of a spring for turning said drum to maintain the trolley rope taut, a ratchet, a centrifugal dog adapted to engage said ratchet, and a spring at all times connecting said dog and drum to cause said dog and drum to rotate together during the unwinding movements of said drum and forming the sole driving connection between said drum and dog.

12. In a trolley catcher, the combination with a winding drum, of means for stopping said drum, comprising a centrifugal dog, a relatively stationary part with which said dog is adapted to engage, and means connecting said drum and dog to normally rotate them together including an element for cushioning the impact when said dog engages said stationary part.

13. In a trolley catcher, the combination with a drum, means for turning said drum to wind up the trolley rope thereon and maintain it taut, a centrifugal dog, a casing, and means located between said dog and casing adapted to be engaged by said dog to stop the rotation of said drum, of means for actuating said dog and retaining it in the path of said stoppage means after the dog has stopped the rotation of the drum in rope paying out direction and during the rope winding up action of said drum incident to a rebound of the trolley pole.

14. In a trolley catcher, the combination with a drum, a spring for turning said drum to wind up the trolley rope thereon and maintain it taut, a centrifugal dog, a casing, and a ratchet in said casing and arranged to be engaged by said dog to stop the rotation of said drum, of means for actuating said dog and retaining it in engagement with said ratchet during the rebound of the trolley pole.

15. In a trolley safety device, the combination of a casing, a winding drum, means for rotating said drum to maintain the trolley rope taut, and mechanism interposed between said casing and drum for stopping the rotation of the drum and maintaining said mechanism in operative position during rebound of the trolley, the said mechanism comprising a ratchet, a centrifugal dog arranged to engage therewith, and a spring arranged to exert more resistance to the movement of the drum relative to said centrifugal dog in one direction of rotation than in the other direction of rotation.

16. In a trolley safety device, the combination of a casing, a winding drum, means for rotating said drum to maintain the trolley rope taut, and mechanism interposed between said casing and drum for stopping the rotation of the drum and maintaining said mechanism in operative position during rebound of the trolley, the said mechanism comprising a ratchet, a centrifugal dog, arranged to engage therewith and a spring arranged to exert more resistance to the movement of the drum relative to said casing when said dog is in engagement with said ratchet and said drum is rotating in one direction than when said dog is in engagement with said ratchet and said drum is rotating in the opposite direction.

17. In a trolley safety device, the combination of a winding drum, a dog-carrying member separate from said drum, a centrifugal dog upon said member, and a driving connection between said drum and dog-carrying member comprising a looped flat spring connected at the loop to the drum and having the free end of its outside leg connected to said dog-carrying member and the end of its inside leg frictionally engaged between said dog-carrying member and the outside leg of the loop.

18. In a trolley catcher, the combination of a drum, a spring for turning said drum to wind up the trolley rope thereon, a centrifugal dog, a casing having stops adapted to be engaged by said dog to stop the rotation of said drum, and means interposed between the drum and dog for transmitting the movement of the drum to the dog and for cushioning the impact incident to the action of said dog to stop the rotation of said drum.

19. In a trolley catcher, the combination with a drum, a spring for turning said drum to wind up a trolley rope thereon, a casing, and stops therein, of means for stopping the rotation of said drum relative to said stops, comprising a centrifugal dog and a cushioning spring.

20. In a trolley catcher, the combination with a drum, a spring for turning said drum to wind up a trolley rope thereon, a casing, stops, and a centrifugal dog arranged to

engage one of said stops to stop the rotation of the drum, separate from said drum winding spring located between said drum and casing for actuating said dog and for cushioning the impact incident to the action of said dog to stop the rotation of the said drum.

21. In a trolley catcher, the combination of a stationary member, a rotatable member 10 on which a trolley rope is wound, a spring for rotating said rotatable member in one direction, a two-part mechanism between said members for stopping the rotation of the drum comprising a series of ratchet teeth 15 and a dog arranged to engage one of said teeth to stop said drum, and means interposed between one part of said drum stopping mechanism and one of said members for cushioning the impact action of said dog.
22. In a trolley catcher, the combination of a drum, means for turning said drum to wind up the trolley rope thereon and maintain it taut, a centrifugal dog, a casing, means between said dog and casing arranged 20 to be engaged by said dog, and connections between said dog and drum permitting relative movement between them about the axis of the drum, and operating to retain said dog in the path of the stoppage means during rebound of the trolley pole.

23. In a trolley catcher, the combination with a trolley rope winding drum, and a spring for turning said drum to maintain the trolley rope taut, of a series of teeth, a 35 centrifugal dog arranged to engage one of said teeth, and a yielding driving connection between said drum and dog for actuating the latter, the said driving connection being at all times active, whereby the dog is maintained in the path of the teeth during 40 the rebound of the trolley pole.

24. In a trolley safety device, the combination of a casing, a winding drum therein, means for rotating said drum to maintain 45 the trolley rope taut, and mechanism between said casing and drum for stopping the rotation of the drum and maintaining its engaging parts in operative relation during rebound of the trolley, the said mechanism comprising a ratchet carrying member, a centrifugal member arranged to engage therewith and a spring for actuating one of said members and arranged to exert more 50 resistance to the movement of the drum relative to said centrifugal member in one direction of rotation than in the other direction of rotation.

25. In a trolley control device, the combination with a casing, a drum rotatably 60 mounted therein and means for rotating said drum in one direction, of a series of ratchet teeth carried by said casing, a member rotatably mounted on an axis coincident with the axis of the drum, a centrifugal dog carried 65 by said member and arranged to engage said

teeth, and connections between said drum and said member for actuating the latter and permitting relative movement between said drum and member when the dog engages a tooth whereby the drum is cushioned.

70

26. In a trolley control device, the combination with a casing, a drum rotatably mounted therein and means for rotating said drum in one direction, of a series of ratchet teeth carried by said casing, a member rotatably mounted on an axis coincident with the axis of the drum, a centrifugal dog carried by said member and arranged to engage said teeth, and connections between said drum and said member for actuating the latter and permitting relative movement between said drum and member when the dog engages a tooth whereby the drum is cushioned, the said connections operating to maintain the dog in operative relation to said ratchet teeth during rebound of the trolley.

75

27. In a trolley control device, the combination with a casing, a drum rotatably mounted therein and means for rotating said drum in one direction, of a series of ratchet teeth carried by said casing, a member rotatably mounted on an axis coincident with the axis of the drum, a centrifugal dog carried by said member and arranged to engage said teeth, and connections between said drum and said member for actuating the latter and operating to maintain said dog in operative relation to said ratchet teeth during 90 rebound of the trolley.

95

28. In a trolley control mechanism a casing, a drum to which a trolley rope is connected, means for rotating the drum to wind the rope thereon, and means for stopping the rotation of said drum in the rope unwinding direction, the said means being dependent upon centrifugal force for its operation and constructed and arranged to act yieldingly in stopping the rotation of the drum in rope paying out direction and then hold the 105 drum at said stopped position.

110

29. In a trolley control mechanism a casing, a drum to which a trolley rope is connected, means for rotating the drum to wind the rope thereon, and means for yieldably stopping the rotation of said drum in the rope unwinding direction, the said means permitting rotation of the drum in the rope winding direction during rebound of the trolley without affecting the operative relationship of said stopping means.

115

30. In apparatus of the character described, the combination of two members one of which comprises a drum rotatable relative to the other member and arranged to have a rope wound thereon and unwound therefrom, means for rotating the drum in one direction to wind the rope thereon, and means for yieldingly stopping the rotation of the drum in the rope unwinding direction.

120

130

- tion, the said means including an intermediate member arranged between said relatively movable members, a pair of inter-engaging devices between one side of said intermediate member and the adjacent member and connecting devices interposed between the opposite side of said intermediate member and the other member, one of said connecting devices being at all times active.
31. In apparatus of the character described, the combination of two members one of which comprises a drum rotatable relative to the other member and arranged to have a rope wound thereon and unwound therefrom, means for rotating the drum in one direction to wind the rope thereon, and means for yieldingly stopping the rotation of the drum in the rope unwinding direction, the said means including an intermediate member arranged between said relatively movable members, pawl and ratchet devices between one side of said intermediate member and the adjacent member and connecting devices, one of which comprises a spring interposed between the opposite side of said intermediate member and the other member.
32. In a trolley catcher, the combination with a casing and a trolley rope adapted to be connected to a trolley pole, of a drum mounted in said casing, means for rotating said drum to wind the rope thereon, and means for controlling the unwinding of the rope when the trolley pole leaves the overhead wire, the said means including pawl and ratchet mechanism and being constructed and arranged to maintain the pawl in operative relation to the ratchet during rebound of the trolley pole.
33. In a trolley catcher, the combination with a casing and a trolley rope adapted to be connected to a trolley pole, of a drum mounted in said casing, means for rotating said drum to wind the rope thereon, and means for controlling the unwinding of the rope when the trolley pole leaves the overhead wire, the said means including pawl and ratchet mechanism with a centrifugal operated pawl, the said means being constructed and arranged to maintain the pawl in operative relation to the ratchet during rebound of the trolley pole.
34. In a trolley catcher, the combination with a casing and a trolley rope adapted to be connected to a trolley pole, of a drum mounted in said casing, means for rotating said drum to wind the rope thereon, and means for controlling the unwinding of the rope when the trolley pole leaves the overhead wire, the said means including a centrifugal pawl and ratchet mechanism and being constructed and arranged to maintain the pawl in operative relation to the ratchet during rebound of the trolley pole.
35. In a trolley catcher, the combination with a casing and a trolley rope adapted to be connected to a trolley pole, of a drum mounted in said casing, means for rotating said drum to wind the rope thereon, and means for stopping the rotation of said drum relative to said casing when the speed of rotation of said drum reaches a predetermined rate and for permitting rebound of the trolley pole and consequent slack of the trolley rope while maintaining said stopping means in operative relation to stop the rotation of the drum in rope paying out direction when the rope again becomes taut immediately following the rebound of the trolley pole.

In testimony whereof I affix my signature, in the presence of two witnesses.

MELVIN A. YEAKLEY.
